(57) **CLAIM**

The ornamental design for a blender base, as shown and described.

DESCRIPTION

FIG. 1 is a front view of a blender base showing my new design;

FIG. 2 is a rear view thereof;

FIG. 3 is a left side view thereof;

FIG. 4 is a right side view thereof;

FIG. 5 is a top view thereof;

FIG. 6 is a bottom view thereof;

FIG. 7 is a left, front perspective view thereof; and,

FIG. 8 is a bottom, rear perspective view thereof.

The broken lines in the drawings are for showing portions of the blender base that form no part of the claimed design.

1 Claim, 8 Drawing Sheets
